CONTAINER AND CLOSURE THEREFOR

Arthur John Williams, Poole, and William Johnstone Dyson, Bournemouth, England, assignors of one-third to The Wallis Tin Stamping Company Limited, Poole, England, a British company

Application February 8, 1946, Serial No. 646,292
In Great Britain January 22, 1945

Section 1, Public Law 690, August 8, 1946
Patent expires January 22, 1965

3 Claims. (Cl. 215—38)

1

This invention is for improvements in or relating to containers and closures therefor.

The invention is concerned with closures of the Phoenix type, namely the type in which an inner flanged metal cap closes the mouth of the container and reaches down around the outside thereof, being held in position by a removable metal band, the edges of which are turned over onto the top of the cap and under a flange on the container. To render the inner cap suitable for re-sealing the container after say a portion of its contents has been removed, various proposals have been made involving the provision of lugs on the cap and alterations to the flange on the container. The present invention has for one of its objects to provide a re-sealable inner cap which saves metal and produces a satisfactory and neat closure.

According to the primary feature of the invention there are provided a container and closure of the type described which are characterised in that the flange on the container is circumferentially grooved between its lower edge and the top of the container, and in that the flange on the inner cap is provided with extensions each reaching around a substantial part of the circumference of the flange with its lower edge inwardly directed to clip into said groove, and hold the cap in sealing position. Thus although the outer band has been destroyed in removal, the inner cap can readily be used for re-sealing, the extensions being sprung into the groove.

Conveniently the inner cap has two of the said extensions which are diametrically opposed and each reaches around about one quarter of the circumference of the flange. This construction will be found to impart adequate retentive action to the extensions without involving the use of much metal. Metal is also economised if, as is preferred, the extensions are each composed of a single thickness of metal slightly less in depth than the depth of the remainder of the flange and slightly inclined inwardly without being curled. The extensions may have rounded lower corners.

According to another feature of the invention, the groove in the container is interrupted to provide an abutment which will be engaged by the cap extensions when the latter are in the groove, if the cap is rotated. The purpose of this abut-

2

ment is to enable the cap to be readily removed merely by rotating it, the abutment serving to wedge out of the groove the extension which engages it. So as not to interfere with the easy assembly of the cap on the container initially, it is preferred that there shall be only a single circumferentially small interruption in the groove. For instance in a groove 5 1/2 inches in circumference the abutment may occupy only about 1/8 of an inch of that circumference. In some cases, however, instead of having the interruption circumferentially small it may be larger, say about one quarter of the circumference. This enables the cap to be removed more easily, but entails more care in securing it in place. The walls of the interruption may diverge as they merge into the base of the groove to provide wedging surfaces for engagement by the corners of the cap extensions.

20 For a more complete understanding of the invention, there will now be described, by way of example only and with reference to the accompanying drawings, certain constructions of container and closure according to the invention. It is to be understood, however, that the invention is not restricted to the precise constructional details set forth.

In these drawings:

Figure 1 is an elevation of the upper part of one form of container according to the invention, with the closure in place thereon, the closure being shown mainly in section,

Figure 2 is a view similar to Figure 1, but with part of the closure broken away and other parts shown in outside elevation,

Figure 3 is a section on the line 3—3 of Figure 2,

Figure 4 is a partial view corresponding to Figure 3, but with the outer band of the closure removed and the metal cap in the course of removal,

Figure 5 is a view corresponding to Figure 1, but viewed from a point 90° around the circumference of the assembly from the view point of Figure 1 and with the outer band of the closure removed and the metal cap in the course of removal,

Figure 6 is a composite view, partly in section, showing separately the upper part of another form of container according to the invention, and the two parts of the closure before the closure is secured in place, and

Figure 7 is a section through the container on the line 7—7 of Figure 6.

Like reference numerals indicate like parts throughout the drawings.

Referring firstly to Figures 1 to 5, the container 10 has a flange 11, 12 around its mouth, the two parts of the flange being separated by a groove 13 which is a plain annulus, i. e. is not helical. The lower edge of the flange part 11 has a corner which is almost square, usually being about 110°. A Phoenix closure is shown, consisting of an inner metal cap 14 with a fluted flange 15, and a removable band 16, one end of which is slipped through a slit in the other end and turned back to secure the band in place. The edges of the band 16 are turned over on to the top of the cap 14 and under the said almost square corner of the flange part 11, the latter operation being carried out after the closure has been placed in position on the container. The cap 14 has a sealing washer or cushion 17 inside it. When the container is first opened, the band 16 is, as usual, removed and discarded, but the cap 14, according to the present invention, can be readily and efficiently used for re-sealing purposes. Its flange 15 has two diametrically opposite extensions 18 each extending around a substantial part of the circumference (say about one quarter as shown in the drawings). The extensions 18 are slightly less in depth than the flange from which they extend, and each is only a single thickness of metal slightly inclined inwardly without being curled into a bead. The lower ends of the extensions spring into the groove 13 in the container and have sufficient retentive action to hold the cap in sealing position. The lower edges of the extensions 18 may, if the flange 12 is about 5½ inches in outside diameter, be set at a diameter about $\frac{1}{16}$ of an inch less than the diameter of the said flange.

The overall diameter of the flange part 11 on the container is sufficiently larger than the overall diameter of the flange part 12 so that the band 16 shall be an equally close fit on the cap flange 15 and the container flange part 11. The continuity of the groove 13 is interrupted by a circumferentially very small abutment 19 having sloping sides 20. If the flange 11 is about 5½ inches in outside diameter, the abutment 19 may be about $\frac{1}{2}$ of an inch at the surface, widening to about $\frac{3}{2}$ of an inch at the base of the groove. It extends completely across the latter. The sloping sides 20 provide wedging surfaces to be engaged by the rounded corners 21 of the cap extensions 18, if the cap is rotated when the extensions are in the groove 13. Thus the cap can be readily removed, merely by rotating it, the procedure being shown in Figures 3, 4 and 5. In Figure 3, the cap is in sealing position with its extensions 18 clear of the abutment 19. In Figure 4, the cap is shown as having been rotated in the direction of the arrow, causing the rounded corner 21 of one of the cap extensions 18 to encounter and ride outside the abutment 19. The metal of the cap will afford sufficient spring to accommodate this without taking a permanent set. The cap can then be lifted away, as shown in chain lines in Figure 5, turning as on a hinge about the other cap extension 18. The single abutment 19, being circumferentially small, will not be likely to interfere with the initial assembly of the closure on the container, even if this is effected by a machine, as the gaps between the extensions 18, which in the construction shown total about one half of the circum-

ference, will afford ample circumferential scope for the extensions to avoid the abutment in the assembly operation. Re-sealing by hand will, of course, be very easy as the user merely has to bring a gap between the cap extensions 18 opposite to the abutment 19 and press the cap home.

In some cases, the interruption in the groove 13 may be larger than is shown in Figures 1 to 5. For instance in Figures 6 and 7, the interruption 10 23 is about one quarter of the circumference. This enables the cap to be removed more easily, but entails more care in securing it in place.

It is to be understood that the invention is not restricted to the precise constructional details set forth.

We claim:

1. The combination of a container having an external flange around its mouth, which flange is circumferentially grooved between its lower edge and the top of the container, which groove is interrupted to provide a single abutment, of a two-part closure comprising an inner flanged metal cap to close the mouth of the container and reach down around the outside thereof, 20 which cap flange is provided with two diametrically opposite extensions each reaching around about one-quarter of the circumference of the flange with its lower edge inwardly directed to clip into the groove in the container flange and hold the cap in sealing position and also to engage the said abutment when the extensions are in the groove, if the cap is rotated, and a removable metal band the edges of which are turned over on to the top of the said cap and under the flange on the container.

2. The combination of a container having an external flange around its mouth, which flange is circumferentially grooved between its lower edge and the top of the container, which groove is interrupted to provide a single circumferentially small abutment, of a two-part closure comprising an inner flanged metal cap to close the mouth of the container and reach down around the outside thereof, which cap flange is provided with two diametrically opposite extensions each reaching around about one-quarter of the circumference of the flange with its lower edge inwardly directed to clip into the groove in the container flange and hold the cap in sealing position and 40 also to engage the said abutment when the extensions are in the groove, if the cap is rotated, and a removable metal band the edges of which are turned over on to the top of the said cap and under the flange on the container.

3. The combination of a container having an external flange around its mouth, which flange is circumferentially grooved between its lower edge and the top of the container, which groove is interrupted to provide a single abutment, of a two-part closure comprising an inner flanged metal cap to close the mouth of the container and reach down around the outside thereof, which cap flange is provided with two diametrically opposite extensions each reaching around about one-quarter of the circumference of the flange with its lower edge inwardly directed, without being curled, to clip into the groove in the container flange and hold the cap in sealing position and also to engage the said abutment when the extensions are in the groove, if the cap is rotated, and a removable metal band the edges of which are turned over on to the top of the said cap and under the flange on the container, the walls of which abutment diverge as they merge into the 50 base of the groove to provide wedging surfaces

2,438,689

5

for engagement by the corners of said extensions,
which corners are rounded.
